(57) **CLAIM**

The ornamental design for an illuminated buckle, as shown and described.

DESCRIPTION

FIG. 1 is a perspective view of an illuminated buckle according to an embodiment of the new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is another perspective thereof; and,

FIG. 9 is an enlarged view of a section indicated in FIG. 1. The features shown in broken lines in the drawing depict environmental subject matter only and form no part of the claimed design.

1 Claim, 7 Drawing Sheets
